TAMPERPROOF CLOSURE

Donald H. Tilson, New Kensington, Pa., assignor
to Aluminum Company of America, Pittsburgh,
Pa., a corporation of Pennsylvania

Original application January 8, 1942, Serial No.
426,005. Divided and this application May 29,
1942, Serial No. 444,953

5 Claims. (Cl. 215—38)

This application, which is a division of my co-pending application Serial No. 426,005 for improvements in Tamperproof closure, filed January 8, 1942, relates to an invention in closures of the type reformed on a container finish, and more particularly to such closures when made of pliable metal such as aluminum.

An object of this invention is to provide a pliable metal closure adapted to have a flange inturned under a shoulder of a container finish which is tamperproof.

Another object is to provide a tamperproof closure which, because of fractured or mutilated portions thereof, will indicate its initial removal from a container to which it has been reformed.

A closure embodying the invention permits no access to the interior of a container without apparent irreparable and telltale damage to the closure. This damage need not impair the further use of the closure but will always serve to evidence its initial removal from a container to which it has been reformed. The objects of this invention appear more clearly by reference to the drawing of a simple embodiment thereof.

Fig. 1 is a plan view of a closure embodying the tamperproof feature of the invention;

Fig. 2 is a side elevation of the closure shown in Fig. 1 before its reformation on a container;

Fig. 3 is a side elevation of the tamperproof closure as it appears reformed on a container; and

Fig. 4 is a vertical section of the tamperproof closure reformed on a container.

Referring now to the drawing, the closure 10 may be made of any pliable material capable of permanent deformation and ready tearing. Thin metal, preferably aluminum, is suitable. The closure 10 is cylindrical or cup-like in its preliminary shape and may have its skirt reformed into close contact with the finish or shoulder at the neck of container 11. There is provided slightly above the bottom of the skirt and extended vertically upward about half the skirt length a scored, corrugated or fluted band 12. For reasons appearing hereinafter I prefer to locate band 12 so as to include and extend on both sides of the line along which the cap skirt is folded when reformed to a container. Band 12 may be extended not quite to the edge of the skirt to leave a short unweakened strip 16. Strip 16 offers protection against splitting in normal handling.

Band 12 may be formed easily by the commonly known "knurling" operation which is produced by rotating a tool against the backed up closure

skirt, the tool being milled preferably the width of the band to be formed. The effect of rotating such a tool against the backed up skirt of the closure is to form flutes or corrugations therein. Such forming increases the surface area of the closure section selected for the location of the band 12; that is, the periphery of a cross section taken through the formed band is sinuous and much greater in length than the circumference of the skirt before impressing the band. The necessary effect of forming minute flutes or corrugations is to thin out sections of the skirt. The band is weakened by being so thinned and embrittled by the cold working of the metal resulting therefrom.

I prefer to form this weakened band prior to reforming the cap onto the closure finish, and have found that by properly selecting the tool according to the nature of the material from which the cap is made, it is possible to weaken the band to the extent that it will withstand the bend required to reform the closure on the container finish but will not withstand, without splitting, the reverse bend necessary to pry it therefrom.

The closure set out in the drawing is an example of one of the many types to which my invention is applicable. It may be provided as shown with the usual sealing liner 13 of well known construction and purpose and an ordinary tear tab 14. Beneath the tear tab 14 and over the liner 13 a protective and/or reinforcing disc 15, preferably of metal, may be provided. Disc 15 may be used to prevent entry into the container through the sealing liner 13 when the tear tab 14 is lifted. In a closure of the type where a tear tab is located depending from the skirt, or in a closure where no means of any kind are provided for facilitating opening, disc 15 may not be required.

The closure is placed over a container and reformed thereon in the usual manner. The normal reforming operation produces a gradual, uniform pressure either by rolling or squeezing on the section being reformed. Such reforming pressure will not split the closure skirt.

The closure, when reformed to a container as shown in Figs. 3 and 4, effects a tamperproof package. Any attempt to pry the flange from under the shoulder of the container results in splitting the closure skirt. An attempt of this sort would include the insertion of an instrument such as a blade between the edge of the closure skirt and the neck of the container. Before spreading force applied through the instru-

ment can accomplish its purpose, strip 16 will sever. A split through strip 16 will immediately carry over into the adjacent part of weakened band 12 lying in the undeturned flange and progress up around the shoulder and into the straight sides of the closure skirt through the upper portion of band 12 where it will be readily visible. This visible split, serving as an indicator, will prevent unnoticed removal of the closure from the container.

I do not mean to limit my invention to the closure represented in the drawing or to one formed only in the manner described above. They are but examples. My invention encompasses, and I mean to include therein, other embodiments and variations which will be apparent at once to those skilled in the art.

I claim:

1. A tamperproof package comprising a container having a shouldered finish, a drawn pliable closure reformed thereon having a lower skirt portion thereof formed as a flange beneath said shoulder, a circumferential weakened section of vertical knurling formed in said skirt, said section being disposed so as to begin substantially at the bottom of said skirt and traverse said flange to substantially above the same. 20
2. A drawn pliable closure for a container comprising a top portion and a depending continuous skirt, a circumferential weakened band of vertical furrows formed in said skirt in spaced rela- 25

tion to the lower edge of said skirt, said band being adapted to be reformed in part under the shoulder of the container finish.

3. In combination, a container having a shouldered finish and a drawn tamperproof closure, said closure comprising a top portion, a depending continuous skirt, a circumferential weakened band of vertical furrows formed in said skirt in spaced relation to the lower edge thereof, and a flange formed from the lower portion of said furrowed band and disposed under the shoulder of said container finish.

4. A pliable metal closure for a container comprising a top portion and a depending skirt, said skirt having a circumferential thinned and embrittled band sinuous in cross section in spaced relation to its lower edge, said band being adapted to be reformed in part under the shoulder of the container finish.

5. A package comprising a container having an exterior shoulder and a pliable metal closure having a top portion and a depending skirt with its lower edge reformed as a flange under said shoulder, a circumferential thinned and embrittled band sinuous in cross section formed in said skirt in spaced relation to the lower edge thereof and traversing said flange to substantially above the same, whereby said band will split vertically when said flange is forced from beneath said shoulder.

DONALD H. TILSON.
